WATER TUBE BOILER

Friedrich Wempe, Kassel-Wilhelmshohe, Germany, assignor to Schmidt'sche Heissdampf-Gesellschaft m. b. H., Kassel-Wilhelmshohe, Germany

Application February 24, 1933, Serial No. 658,319
In Germany March 2, 1932

5 Claims. (Cl. 122—265)

In the case of water tube boilers having a water circulation through risers forming the part of the bank lying nearer to the furnace and downcomers forming the part of the bank more remote 5 from the furnace there are, as is well known, tubes in the intermediate region between the two groups in which circulation is defective these tubes becoming risers or downcomers depending upon the load on the boiler. In order to minimize the 10 danger of corrosion in these tubes, it has been suggested in the past to place them so that they are swept only by gases which have a relatively low temperature. It is, however, not always easy to adopt such an arrangement, and in addition 15 even when it is adopted there is no absolute guarantee that it will entirely prevent corrosion. The present invention adopts a different method, namely that the circulation shall always be in the same direction in all tubes of the bank so that 20 there will be no tubes in which the circulation is stagnant. For this purpose the invention proposes to arrange in advance of the downcomers separate risers having enlarged heating surface as compared with the surface of the risers ahead 25 of them and with the downcomers. In these risers with increased heat absorbing surface, the proportion of steam in the steam and water mixture is increased because of the greater rate of heat absorption and this assures a rapid upward 30 flow in these tubes. The tubes following these special risers in the direction of gas flow have only the normal heating surface and because of their relatively small heat absorption are certain to act as downcomers. The invention therefore 35 makes it possible to have a perfectly definite line of demarcation at the desired point in the heated water tube bank between the risers and downcomers.

In the drawing, means of carrying out the 40 invention are illustrated.

Fig. 1 is a vertical section through a semi-vertical water tube boiler. Fig. 2 shows a variation in a similar boiler. Fig. 3 is a cross section on line 3—3 of Fig. 2, and Fig. 4 shows a further 45 variation in a similar boiler.

The semi-vertical tube boiler of Fig. 1 is a marine boiler of the well known A-type. It has two lower drums 1—1, an upper drum 2, and two banks of tubes 3—3 arranged in the shape of a 50 roof over the furnace. The gases of combustion flowing toward the stack connection 4 flow across the tube banks in a direction generally transverse to the tubes. 5 designates the risers lying in the front portion of the tube bank and therefore 55 touched first by the hot gases, while 6 designates

the downcomers forming the farther portion of the bank as regards the gas flow. The risers 5 and the downcomers 6 are formed by smooth tubes, straight for the major portion of their lengths. In accordance with the invention there is arranged between the two groups 5 and 6 of each bank a row of zig-zag tubes 7 whose heat absorbing surface is materially larger than that of the tubes 5 and 6. Although the temperature of the gases has already been lowered by their giving up heat to the risers 5 when they arrive at the tubes 7, nevertheless these tubes can on account of their increased heating surface still absorb a relatively large amount of heat. As a consequence there is still a rapid vaporization in the tubes 7 so that the proportionate part of steam in the steam and water mixture in these tubes is relatively large. The downcomers 6 following the tubes 7 have in comparison with the tubes 7 a small heat absorbing surface. In addition, the heating gases have been considerably cooled when they reach these tubes. The steam generation in the downcomers 6 is therefore so small that it does not interfere with the downward flow in these tubes. Just as in the risers 5 and 7, a unidirectional water circulation is therefore also assured in the downcomers 6. There are no tubes in the bank in this new form of boiler with indeterminate or stagnant circulation.

In the form of the invention shown in Fig. 2 85 there are inserted between the risers 5 at the front and the downcomers 6 at the rear, two rows of tubes 8 and 9 having an enlarged heat absorbing surface. Different from the form of Fig. 1, the increase in the heating surface in this 90 case is not obtained by giving these tubes a zig-zag form but by providing them with external ribs and flanges. The tubes 8 are provided with longitudinal flanges 10 and the tubes 9 with circumferential ribs 12. As far as carrying out the 95 invention is concerned, it is immaterial which of these means is utilized to increase the heat absorbing surface of these special risers. The action of this arrangement and particularly the action of the special tubes with increased heat 100 absorbing surface is obviously the same as that pointed out in connection with the form of Fig. 1 above.

In the illustrative example of Fig. 4 only the first two rows of risers 5 which will absorb heat 105 both by radiation from the furnace and convection from the gases passing through the bank, and the downcomers 6 at the rear of the bank are given the shape of smooth generally straight tubes. The rows of tubes 13, 14 and 15 lying 110

between them are given zig-zag form, and they are given such form that the surface increases progressively in the direction away from the furnace so that the rear row of risers 15 has the

5 greatest amount of heat absorbing surface. By this gradual increase of heating surface, the effect of the gradual decrease in temperature of the heating gases is at least in part counteracted and a steam and water mixture is obtained in each
10 10 of these rows composed of approximately the same percentage of steam and water.

It may be mentioned that it is old to connect radiantly heated evaporating tubes, extending vertically below the lower drum and lining the
15 furnace wall below it, into the lower drum of a semi-vertical tube boiler and to lead the steam and water mixture coming from them through a conducting means to the tubes of the bank which receive the least amount of heat. This is done
20 to avoid the mixture in the front rows of the bank having too much steam in it thereby endangering these tubes by overheating. The present invention has nothing in common with such an arrangement since in such vertical banks
25 there are no downcomers at all, but all of the tubes of the bank act as risers and large unheated downcomers are employed.

Contrasted with this the present invention always has a portion of the heated tubes of the
30 bank forming downcomers and the invention has for its purpose to effect a definite division for all conditions of operation between the risers and downcomers of the heated bank of tubes.

While the invention has been described in the
35 above in connection with a single type of boiler, it will be obvious that it is not limited in this respect but can be utilized in connection with various types of water tube boilers. The appended claims are intended to cover this as well as other
40 variations which may be made in practicing the invention.

What I claim is:

1. In a boiler, a bank of tubes heated by the products of combustion passing through the bank
45 on their way from the furnace to the stack in a direction generally transverse to the bank, that portion of the tubes of the bank nearer the furnace acting as risers and the remaining ones as

downcomers, those of the riser tubes with which the gases come in contact last having a greater external heat-absorbing surface than the other risers.

2. In a boiler, a bank of tubes heated by the products of combustion passing through the bank on their way from the furnace to the stack in a direction generally transverse to the bank, that portion of the tubes of the bank nearer the furnace acting as risers and the remaining ones as
85 downcomers, those of the riser tubes with which the gases come in contact last having a greater external heat-absorbing surface than the downcomers with which the gases come in contact next after leaving the risers.

3. In a boiler, a bank of tubes heated by the products of combustion passing through the bank on their way from the furnace to the stack in a direction generally transverse to the bank, that portion of the tubes of the bank nearer the furnace acting as risers and the remaining ones as
95 downcomers, those of the riser tubes with which the gases come in contact last having a greater external heat-absorbing surface than any of the downcomers.

4. In a boiler, a bank of tubes heated by the products of combustion passing through the bank on their way from the furnace to the stack in a direction generally transverse to the bank, that portion of the tubes of the bank nearer the furnace acting as risers and the remaining ones as
105 downcomers, those of the riser tubes with which the gases come in contact last having a greater external heat-absorbing surface than the other risers or the downcomers.

5. In a boiler, a bank of tubes heated by the products of combustion passing through the bank on their way from the furnace to the stack in a direction generally transverse to the bank, that portion of the tubes of the bank nearer the furnace acting as risers and the remaining ones as
115 downcomers, the risers comprising a plurality of rows successively touched by the gases, the tubes of each row having a greater heat absorbing surface than the tubes of the preceding row, the
120 downcomers all having heat absorbing surface no greater than the tubes of the first row of risers.
